UNITED STATES PATENT OFFICE

99,866

DESIGN FOR A BOOTH SEAT

Wolfgang Hoffmann, Batavia, Ill., assignor to
The Howell Company, St. Charles, Ill., a cor-
poration of Illinois

Application March 30, 1936, Serial No. 61,842

Term of patent 3½ years

To all whom it may concern:

Be it known that I, Wolfgang Hoffmann, a citizen of the Republic of Austria, residing at Batavia, in the county of Kane and State of Illinois, have invented a new, original, and ornamental Design for a Booth Seat, of which the following is a specification, reference being had to the accompanying drawing, forming a part thereof.

Figure 1 is a perspective view of the booth seat, showing my new design;

Fig. 2 is a side elevation thereof; and

Fig. 3 is a front elevation thereof.

I claim:

The ornamental design for a booth seat, as shown.

WOLFGANG HOFFMANN.
